(57) **CLAIM**

The ornamental design for a flow meter, as shown and described.

DESCRIPTION

FIG. 1 is a perspective view of a flow meter;

FIG. 2 is a top plan view of the flow meter of FIG. 1;

FIG. 3 is a front elevation view of the flow meter of FIG. 1;

FIG. 4 is a right side elevation view of the flow meter of FIG. 1;

FIG. 5 is a rear elevation view of the flow meter of FIG. 1;

FIG. 6 is a left side elevation view of the flow meter of FIG. 1; and,

FIG. 7 is a bottom plan view of the flow meter of FIG. 1. Portions of FIGS. 1 through 7 are shown in broken lines illustrating portions of the article of manufacture that form no part of the claimed design.

It is certified that error appears in the above-identified patent and that said Letters Patent is hereby corrected as shown below:

On the Title Page

Replace the illustrative print figure, as shown on the attached Drawing Sheet, 1 of 7, showing the replacement FIGURE 1

In the Drawings

Replace Drawing Sheets 1-7 with the attached Drawing Sheets 1-7 (FIGURES 1-7)

Signed and Sealed this
Twenty-seventh Day of May, 2025

Coke Morgan Stewart
Acting Director of the United States Patent and Trademark Office
